UNITED STATES PATENT OFFICE

JOSEPH BUXTBAUM, OF BROOKLYN, NEW YORK

KNOCKDOWN WINDOW SCREEN

Application filed April 28, 1927. Serial No. 187,136.

My invention relates to extensible closures and, more particularly, to such devices when applied to window screens.

The present invention is an improvement on the device shown in my U. S. Patent No. 1,610,036, issued Dec. 7, 1926, for window screen. One of the objects of this improvement is to make the aforesaid device adjustable to different size windows or wall openings in general. Another object is to produce "knock down" units which may be readily taken apart and as readily assembled, so that the unit can be shipped or transported in a compact form, and the several elements forming it separately supplied or replaced. A third object is to eliminate the danger attending the usual procedure of fastening suspension means for a screen to the outer surface of the wall of a building, sometimes, at a great height from the ground, by providing a complete unit comprising both the screen and the suspension means therefor through operations performed entirely on the inside of the building when setting up the unit in its place. Other objects will become apparent from the detailed description of my invention which follows.

In the drawings, Figure 1 is a front view of one embodiment of my invention. Figure 2 is a side view thereof when the sectional screen forming a part of my device is raised. Figure 3 is a cross section of the device shown in Figure 1, taken along the line 3—3. Figure 4 is an enlarged detail of the outer frame of the device illustrated in Figures 1 and 2, looking in the direction of the arrow 4 at the bottom of Figure 2. Figure 5 is a cross section taken along the line 5—5 of Figure 4. Figures 6 and 7 are, respectively, a front and a side view of a catch used in connection with my device. Figure 8 is a detail showing how the sectional screen is held in a raised position. Figure 9 is an enlarged corner of such a sectional screen. Figure 10 is an enlarged cross section along the line 10—10 of Figure 9.

Referring to the figures in detail, F is an extensible frame composed of the top stile 1, bottom stile 2, and side stiles 3, and the corner members 4 telescoping with the stiles

1, 2, 3. On the frame F is mounted a frame f made up of two sections, each section comprising longitudinal stiles 5 and transversal stiles 6, and corner members 7 telescoping with the stiles 5, 6. The stiles 5 and 6 are formed by invertedly superimposing two members of U shaped cross section so that the cross section of the stiles is substantially a rectangle. The U shaped members of larger cross section will be denoted throughout by the index (''), those of the smaller cross section, which are invertedly inserted into those of the larger cross section, by the index ('). Thus, the outer U shaped members of the stiles 5 and 6, respectively, are denoted by 5'' and 6'', and the inner U shaped members thereof by 5' and 6'. The corner members 7 are similarly made up of members 7' and 7'' of U shaped cross section, invertedly superimposed, as clearly shown in Figure 10. A mesh 8 is stretched across each one of the sections of the frame f, is bent at its periphery and jammed in between adjacent shanks of the members 5' and 5'' (or 6' and 6'') along that part of the stiles which is not telescoped into a corner 7, and between adjacent shanks of members 5'' and 7'' (or 6'' and 7') along such a corner 7. The mesh 8 is secured to the frame f not so much by the pressure of the adjoining shanks of the U shaped members as by the pressure of the edges of the shanks of 5' (or 6') on the bottom of the members 5'' (or 6''), the ends 9 of the mesh 8 extending into the hollow interior of the stiles, as shown in Figure 10. The amount of telescoping between a stile 5 (or 6) and a corner member 7 is adjustable, as by means of a slot 10 in the member 7' and a short bolt 11 passing through the member 5' (or 6'). The member 5'' (or 6'') is adjustably secured to the member 7'' in a similar manner by a slot in the member 7'' and a short bolt 12 passing through the member 5'' (or 6'').

The stiles of the frame F are made up of sheet metal shaped to conform with the outline of the wall opening. As shown in Figure 3, the side stiles 3 are spaced to abut on the outside casing (for a frame building) or reveal (for a stone or brick building), 13, and

they have a smaller cross section near the window side, to make room for the outside window stop 16. The recess in the stile to allow for the outside window stop is made sufficiently large to provide for all cases and, accordingly, there may be an open space between this portion of the stile and the window stop, but this is of no consequence, since the remaining portion of the stile is made to fit closely to the reveal or casing 13. The stiles 3 are secured to the outside stops 16, as by means of screws 17, which pass through the reduced portions, 14, of the stiles 3. Only one window, 15, is shown, of the pair which make up a complete sash window. The corner members 4 are shaped to correspond to the form of the stiles and are adjustably secured thereto in a manner similar to that of frame *f*. At 18, the stiles 3 are shaped to form grooved guides for the pins 19 which extend laterally from the corner members 7, with stops 20 therefor at different heights in the flange 21. The flange 21 is formed by bending the metal sheet, of which the stile 25 is made, upon itself, as shown in the drawing. A second bend upon itself of this sheet is shown at 22, forming an inclined flange which rests on the stiles of the frame *f* and covers up the openings or cracks between the frames *f* and *F*, so that no flies or other insects may pass the screen. To take care of the space uncovered when the frames are telescopically extended, I may provide extensions of the flanges 22 slideable therein and held 35 by friction or otherwise between the two walls thereof, but I prefer to make similar flanges 23 on the corner members 4, into which the flanges 22 may telescope in unison with the telescoping of the other portions of the stiles. 40 The two sections of the frame *f* are linked together for angular motion relatively to one another and to the frame *F*. No especial form of linkage is claimed in the present invention, a pivotal connection 24 being shown 45 in Figure 2. At its upper end, the frame *f* is suspended from the frame *F*, as by means of a hook 25 and an eye 26. When the screen is in closed position, it is locked by means of a catch 27 revoluble on a pivot 28. The center of gravity of the catch 27 is below the point 28, when in the position shown in Figures 6 and 7, so that, when released, it automatically assumes this position, at which time the boss 30 engages the stile 5 and holds 55 the catch in proper alignment. When the catch is operative to lock the screen, the inclined arm 29 frictionally engages the flange 22 of the frame *F*. The catch is manipulated by taking hold of the boss or handle 31 which 60 projects at a right angle from the main body thereof.

The manner of installing such a screen as herein described, received in "knocked down" condition, will now be briefly explained. 65 First, the outer frame *F* is assembled, the cor-

ner members 4 being secured to the telescoping stiles 1, 2, 3, after the frame has been extended to the desired size. Next, each section of the screen is assembled as follows. The members 5" and 6" of the stiles 5 and 6 are telescoped into the corner members 7" to make up such lengths for the four sides of the frame *f* as would make the frame *f* fit into the opening of the frame *F*, whereupon the members 5" and 6" are secured to the corner member 7" in the manner described hereinbefore. A mesh 8, exceeding the area of the section of the frame *f*, is placed over the section in a stretched condition, and is bent over the edges of the members 5" and 6" and over the adjoining edges of 5" and 7", and 6" and 7", at the corners, the bent portions of the mesh being somewhat greater than the depth of the U's. Then the members 5' and 6' are telescoped into the corner members 7' to the right lengths and secured to one another, thus forming an inner framework which may be inserted into the framework of the members 5", 6" and 7". When this inner framework is inserted into the outer one, the bent portions of the mesh 8 are jammed in between the adjoining shanks of the members 7' and 5" and of the members 7' and 6", at the corners, and between the members 5' and 5" and the members 6' and 6", beyond the corners, and are firmly held by the pressure of the edges of the shanks of 5' and 6" on the bottom of the members 5" and 6", beyond the corners, and, at the corners, by the pressure of the adjoining edges of the members 5', 7' and 6', 7', on the bottom of the members 5" and 6". This secures the mesh and the two sections of the screen are completed and ready to be linked together, after which the frame *f* is mounted in the frame *F* in the manner hereinabove described.

It only remains to erect the complete unit, so assembled, in its place. This may be done by fitting the unit into the wall opening, operating entirely from the inside of the building, and securing it in place by screwing the stiles 3 to the window stops 16, as above explained.

When standard sizes of window openings are available, or when standard sizes of screens are desired, I may omit the telescoping feature from one or the other, or from both of my frames. The unit would in such a case be made to size and its installation in place proceeded with in the same manner as in the case of the extensible units.

I claim:

1. Locking means between two frames, one of said frames having a projecting flange resting on the second frame, comprising a catch pivoted above its center of gravity in said second frame and provided with an arm adapted to frictionally engage said flange when said catch is in operative position and

with a boss shaped to engage the edge of said second frame when said catch is released, and means for operating said catch.

2. In a window frame provided with a closure suspended from the top of said frame and having laterally projecting pins at the bottom, upright and transverse stiles, each stile formed by a single sheet of metal bent into a main hollow member having a longitudinal groove for the guidance of said pins, said metal sheet bent upon itself to form a flange extending from one side of said groove and provided with stops for said pins, and said metal sheet further bent upon itself to form a second longitudinal flange projecting from said main hollow member at an angle thereto and resting on said closure.

3. In a structure such as is described in claim 2, means for locking the closure mentioned in said claim to the window frame, comprising a catch pivoted above its center of gravity on one of the stiles of said closure and provided with an arm adapted to frictionally engage one of the longitudinal flanges projecting from said window frame and resting on said closure when said catch is in operative position, and with a boss shaped to engage the inner edge of the aforesaid stile when the catch is released, and means for manipulating said catch.

4. A screen comprising a metal frame having longitudinal and transversal stiles and corner members telescoping therewith, each stile and each corner member being composed of invertedly superimposed, frictionally held, stiff channel members, each one of said channel members comprising a base and two sides bounded by plane parallel surfaces perpendicular to said base, means for adjustably securing said stiles and said corner members to one another, and a mesh across said frame bent along its periphery and jammed in between the superimposed members of said stiles and said corner members.

JOSEPH BUxBAUM.
